United States Patent Office

Des. 217,595
Patented May 19, 1970

217,595

NEWSPAPER STAND

Melvin Cohen, 150 Dayton Ave., Passaic, N.J. 07055

Filed Mar. 20, 1969, Ser. No. 16,349

Term of patent 14 years

Int. Cl. D25—04

U.S. Cl. D13—1

FIG. 1

FIG. 2

FIG. 3

FIG. 4

FIG. 1 is a front elevational view of a newspaper stand showing my new design;

FIG. 2 is a right side elevational view thereof;

FIG. 3 is a left side elevational view thereof; and

FIG. 4 is a rear elevational view thereof.

The top and bottom are without ornamentation.

I claim:

The ornamental design for a newspaper stand, as shown and described.
